(57) **CLAIM**

We claim the ornamental design for a racket having bearings in frame, as shown and described.

DESCRIPTION

FIG. 1 is a rear perspective view of a game racket of the present invention.

FIG. 2 is a front plan view of the racket shown in FIG. 1.

FIG. 3 is a top plan view of the racket shown in FIG. 2

FIG. 4 is a left side view of the racket shown in FIG. 2;

FIG. 5 is a right side view of the racket shown in FIG. 2; and,

FIG. 6 is a bottom plan view of the racket shown in FIG. 2.

The ornamental design that is claimed is shown in solid lines in the drawings.
